EXTRUDED CORNER TRIM MEMBER

Irvine Kimmel, 2375 NW. 75th St.,
Miami, Fla. 33155

Filed Aug. 17, 1970, Ser. No. 24,543

Term of patent 14 years

Int. Cl. D25—03

U.S. Cl. D13—1

FIG. 1

FIG. 3

FIG. 2

FIG. 4

FIG. 1 is a perspective view of an extruded corner trim member showing my new design.

FIG. 2 is an end view.

FIGS. 3 and 4 are side elevational views.

I claim:

The ornamental design for an extruded corner trim member, substantially as shown.
